UNITED STATES PATENT OFFICE.

ELVA C. GINGRICH, OF TOULON, ILLINOIS.

SPARK-PLUG.

1,116,584.

Specification of Letters Patent. Patented Nov. 10, 1914.

Application filed January 14, 1914. Serial No. 811,975.

To all whom it may concern:

Be it known that I, ELVA C. GINGRICH, citizen of the United States, residing at Toulon, in the county of Stark and State of Illinois, have invented certain new and useful Improvements in Spark-Plugs, of which the following is a specification.

My invention relates to improvements in spark plugs, and has for its principal object 10 the provision of such a device having a contact member which may be removed therefrom, the device being so constructed that this removal may be effected without stopping the engine, and still retain the compression 15 of the cylinder from which this member is removed.

A further object is the provision of such a device having a removable contact member and also having a valve therein, so that when 20 the contact member is removed, the valve may be closed to retain the compression of the cylinder.

To the accomplishment of the foregoing and such other objects as may hereinafter appear, my invention consists in the combination, construction and arrangement of parts hereinafter described, and then sought to be defined in the appended claims, reference being had to the accompanying drawings forming part hereof, and which shows merely for the purpose of illustrative disclosure, a preferred embodiment of my invention, it being understood that various changes may be made in practice within the 35 scope of the claims, without digressing from my inventive idea.

In the drawings:—Figure 1 is a vertical section through a device constructed according to my invention; Fig. 2 is an end elevation of the same; Fig. 3 is a side elevation of a portion thereof, the valve being indicated in its closed position in dotted lines.

It is found in practice in the operation of internal combustion engines that the spark plugs become fouled from a deposit of carbon or other material, causing ignition trouble, the usual remedy being the stopping of the engine and the removal and examination or repair of the spark plug. Under 45 these conditions, it is my object to obviate the necessity of stopping the engine for such examination or repair and I attain this object by providing a spark plug having a removable contact member and having a valve 50 construction so that the valve may be closed on the removal of the contact member thus

retaining the compression of the cylinder and permitting the engine to run over the other cylinders.

Referring now to the drawings, the numeral 1 designates the body portion of a spark plug constructed according to my invention which is bored as shown and has its lower end screw-threaded as at 2 for attachment to the cylinder of an internal combustion engine, the contact point 3 being provided on this lower end of the body portion. The upper portion of the bore is screw-threaded as at 4 to receive the sleeve member 5 which is correspondingly screw-threaded, and which forms the holder for the contact member. This sleeve 5 has its upper end squared suitably to receive a tool so that it may be screwed into and out of said body portion. This sleeve 5 is bored for a larger portion of its length as at 7, to receive the insulation 8, the contact member 9 passing through said sleeve and insulation and extending to the lower extremity of the body member 1. The upper portion of this contact member is screw-threaded as at 10 to receive the nuts 11 so that the contact member may be assembled in connection with the sleeve 5 and insulation 8. Intermediate its ends this contact member 10 is provided with a tapered enlargement 12 which fits in a correspondingly tapered aperture 13 in the inner end of sleeve member 5, a suitable insulation 14 of mica or similar substance being interposed therebetween. By this construction the contact member is securely connected to its holding sleeve and insulation. As shown, it extends downwardly to provide the second contact point 15 positioned in proximity to the contact point 3.

The body portion of the spark plug is enlarged as at 16 and provided with a slightly tapered aperture 17 extending transversely therethrough, in which aperture is fitted the correspondingly tapered valve member 18 having the reduced screw-threaded extremity 19 to receive nut 20 and washer 21, the latter bearing against the side of the body portion, as shown. This valve member is provided with the enlarged aperture 22, which is positioned in line with the bore of the body portion of the spark plug, so as to permit the passage of the contact member 10 therethrough.

Now then, when ignition or other trouble 110 develops in a cylinder, utilizing a spark plug constructed according to my invention, the

sleeve and holding member 5 is unscrewed from the body portion 1 until the contact point 15 of contact member 10 is withdrawn through the aperture 22 in the valve member 5 18. At this time, the sleeve and holding member 5 is still partially within the body portion 1. The valve 18 is then turned so as to close the passage through the body portion of the spark plug provided by its bore 10 and then the removal of the sleeve and holding member 5 and the contact member 10 is completed, the valve preventing communication between the cylinder and the atmosphere so that the compression is retained 15 therein. The contact point or member may be readily cleaned if necessary, or may be removed and another one substituted in its place, and then the holding sleeve or member 5 is partially screwed into the body portion 20, the valve 18 turned so that its aperture or port 22 is in alignment with the bore of the body portion to permit the passage of the contact member therethrough, the holding sleeve or member 5 being screwed entirely within the body portion of the spark 25 plug to the position shown in Fig. 1.

It is obvious that I have provided a device which operates efficiently as a spark plug, which is simple in construction and 30 cheap to manufacture, and which in addition embodies the advantage of being removable without the necessity of stopping the engine. This latter of course, is the essential feature 35 of my invention, it being readily seen that the accessibility of the parts of the spark plug for examination and repair, is very desirable.

What I claim:—

1. In a spark plug, a body portion bored 40 and adapted to receive a contact member, a contact member removably mounted therein, said body portion having a contact point, and a valve in said body portion adapted to be actuated when said contact member is removed so as to prevent communication of 45 the cylinder with the atmosphere.

2. A spark plug including a body portion bored longitudinally and having a contact point on its lower end, a contact member 50 removably mounted in said body portion and insulated therefrom, and having a contact point adapted to coöperate with said first mentioned contact point, a valve in said body portion having an aperture or port to 55 permit the passage of said contact member therethrough, said valve being adapted to be actuated to close the passage through said body portion on the removal of said contact member.

3. A spark plug including a body portion 60 having a bore therethrough and having a contact point at its lower end, a holding sleeve or member removably mounted in said body portion, a contact member secured to said holding member or sleeve and removable therewith and suitably insulated therefrom, said contact member having a contact point adapted to coöperate with said first mentioned contact point, and a valve in said body portion adapted to close the 70 passage therethrough when the said holding sleeve or member and contact member are removed therefrom.

4. A spark plug including a body portion having a bore therethrough and a contact 75 point at its lower end, the upper portion being internally screw-threaded, a holding sleeve or member externally screw-threaded and adapted to be removably held in said body portion, a contact member held in said 80 holding sleeve or member and extending to the lower portion of said body portion to provide a contact point to coöperate with said first mentioned contact point, a valve in said body portion having an aperture or 85 port to permit the passage of said contact member therethrough, said valve being adapted to be actuated to close the passage through said body portion when the holding sleeve or member and its contact member 90 are being removed from said body portion.

5. A spark plug including a body portion adapted to be attached to a cylinder and having a contact point at its lower end, said body portion being bored and being internally screw-threaded for a considerable portion of its length, a holding sleeve or member externally screw-threaded to correspond with the internally screw-threaded portion 100 of said body portion and adapted to be removed therefrom, a contact member secured to said holding sleeve or member and extending through said bore in the body portion to provide a contact point to coöperate with said first mentioned contact point, said 105 contact member being removable from said holding sleeve or member and being insulated therefrom, and a valve in said body portion adapted to close the passage there-through when the holding sleeve or member 110 and contact member are removed from the body portion.

In testimony whereof I affix my signature, in presence of two witnesses.

ELVA C. GINGRICH.
